CODED TRACK CIRCUIT SIGNALING
SYSTEM

Marcian A. Scheg, Rochester, N. Y., assignor to
General Railway Signal Company, Rochester,
N. Y.

Application March 31, 1942, Serial No. 436,938

10 Claims. (Cl. 246—38)

The present invention relates to railway signaling systems of the coded type and more particularly to a cut section for such systems wherein the code impulses received at the entrance end of a particular section are repeated into the exit end of the section next in the rear thereof and wherein inverse codes are transmitted from the entrance end to the exit end of such particular section.

In signaling systems of the coded track circuit type it is at times necessary to divide a particular block into a plurality of sections each section of which has its own track circuit including its own track source and track relay. This is sometimes necessary because the blocks are longer than the longest operable track circuit and at other times is necessary because ballast resistances are extremely low and changeable. If a block of a coded signaling system is divided into sections the code impulses of one section may be directly repeated into the section next to the rear without first decoding the impulses of the code and then applying a newly generated code to the track circuit in the rear. If, however, the impulses of a code of one track are repeated into the track circuit next in the rear it is important that the apparatus for so repeating the code impulses be of a construction to reproduce the code impulses without either prolonging or decreasing their duration, because if either the impulses are prolonged or are made shorter the difference will become accumulative from section to section so that eventually the track circuit may be either continuously energized or continuously deenergized depending upon whether the impulses became progressively longer or shorter, respectively. This would of course render the system impracticable and probably inoperative.

Another problem that the signaling engineer is repeatedly confronted with is to transmit signal information in a direction opposite to that in which the usual track circuit transmits information. That is, the track circuit ordinarily transmits information from the exit end toward the entrance end of the track section whereas it is at times necessary, as for instance to obtain approach control, to transmit information as to traffic conditions from the entrance end to the exit end of a track circuit. This may be accomplished by transmitting what is known in the art as an inverse code of which each impulse flows between the impulses of the driven code. The foregoing and other advantageous results are attempted to be accomplished by the present invention.

In view of the foregoing and other important considerations it is proposed in accordance with the present invention to create inverse code impulses in response to the operation of a code following track relay and to furthermore repeat impulses into the next track circuit in the rear in response to the operation of such code following track relay through the medium of the same apparatus. In this connection it may be pointed out that the repeated impulses must be of the same duration as the received impulses whereas the inverse code impulses must be of much shorter duration and it is proposed to perform this function through the medium of the same apparatus in spite of the fact that these impulses to be applied by the same apparatus must be of different durations.

It is proposed in accordance with the present invention to employ a track repeater relay which has pick-up and drop-away characteristics such that the duration of front contact closure corresponds substantially to the duration of the code impulse in the track circuit which caused such closure. It is further proposed to employ an impulsive relay which is actuated in one direction through a circuit including a back contact of the code following track relay and a front contact of the code following track repeater relay and which is actuated back to its original position by self-actuation, that is, by a circuit including only its own contacts, this return actuation being specially and appreciably retarded.

Other objects, purposes and characteristic features of the present invention will in part be described hereinafter and will in part be obvious from the accompanying drawing, in which:

Fig. 1 shows a portion of a signaling system embodying the present invention; and

Fig. 2 shows a timing chart useful in studying the functioning of the various relays of the embodiment of the invention illustrated in Fig. 1.

Structure.—The embodiment of the invention illustrated is shown applied to the track rails 10 of a railway signaling system which rails are divided by insulating joints 11 into blocks, of which portions of the block M and the block N only have been illustrated, the block M being divided into sections 1 and 2 by insulating joints 12. Each of the various track sections is provided with a track circuit including a track battery B and a track relay TR, the track battery for the section 2 of block M having been designated B² and the track battery for the section 1 of the block M having been designated B¹. At the entering end 55 of each track section is provided a code following

track repeater relay TP and an impulsing relay IM, this apparatus having for convenience been illustrated only for the section 2 of the block M. As illustrated, the entrance end of the section 2 of the block M is also provided with an inverse code battery IB which may supply code impulses to the entrance end of the track circuit during "off" periods of the driven code for actuating the inverse code track relay ITR located at the exit end of the section 2 of block M.

Although the track relay TR has been illustrated as a neutral relay this relay is preferably polarity responsive in order to render this relay more sensitive and in order to prevent this relay responding to the condenser effect of the track circuit or the inductive kick of the track circuit, as conditions may require, due to the inverse code impulse which is applied to the entrance end of the track circuit just before the code following track relay TR is connected thereto, all in a manner and for reasons more specifically pointed out hereinafter. This track relay TR although it is inherently quick acting is somewhat slow in following the code impulses on the track circuit because the code impulses received are weak and this code following track relay is somewhat slow dropping by reason with its connection in multiple with the ballast of the track circuit as a result of which this ballast may act as a retarding circuit so long as the track relay is connected to the track rails. In other words, the code following track relay TR is slightly slow picking up and is slow dropping to substantially the same extent.

Track repeater relay TP has a resistance unit r^1 in multiple therewith to render this repeater relay slightly slow acting in response to both energization and deenergization thereof. In other words, this repeater relay TP is slightly slow picking up and is slightly slow dropping. This repeater relay TP has been made slightly slow dropping in order that its front contact 15 will be maintained closed long enough after deenergization thereof so that the impulsing relay IM will respond during the drop away time of this code following track repeater relay TP, the impulsing relay IM being actuated to its right-hand position through a circuit including the back contact 14 of the code following track relay TR and the front contact 15 of the code following track repeater relay TP. The pick-up period of the track repeater relay TP is substantially the same as the drop-away period of this relay so that the duration of closure of its front contacts 15 and 16 correspond substantially to the duration of the driven code impulses applied to the track circuit with which this track repeater relay is associated. From this it is readily seen that the code repeated by the contact 16 of the track repeater relay TP from the section 2 into the section 1 next in the rear thereof has impulses of substantially the same duration as the impulses of the driven code from which they were repeated.

The impulsing relay IM is a polar relay of the mag-stick type which is provided with an upper actuating winding and a lower returning winding, which windings have associated therewith relay retarding instrumentalities whereby the relay is very quickly operated from its left-hand to its right-hand position upon the closure of an energizing circuit for the actuating winding of the relay, but is very slowly actuated from its right-hand to its left-hand position upon energization of the returning winding (bottom winding) of the relay. Referring to Fig. 1 it will be observed that the returning winding has in multiple therewith

a resistance unit r^2 which may in combination with this bottom winding constitute a slug for the relay to retard its response to the application of current to either winding of the relay. The retarding action of this resistance r^2 , is however, slight and only retards the operation of the relay to a small extent. The upper or actuating winding, on the other hand, is provided with a rectifier R and a resistance unit r^3 of comparatively low resistance. In other words, the upper winding of this impulsing relay IM is slugged, or retarded, to a much greater extent than is the lower winding of this relay but the retarding feature for the upper winding of this relay functions only to perform its retarding function when the magnetic flux in the relay is increased in a particular direction or is decreased in the opposite direction through the core. In other words, if the actuating winding of the relay is energized as through back contact 14 of relay TR and front contact 15 of relay TP the impulsing relay IM is only slightly retarded in its response, this retardation being performed by the resistance unit r^2 connected across the lower winding of the relay; whereas if the lower winding of the relay is energized through the medium of the contact 20 assuming its right-hand position to produce magnetic flux of the opposite magnetic polarity the impulsing relay is retarded by both the resistance unit r^2 and by the resistance unit r^3 in series with rectifier R. In other words, the impulsing relay IM is lightly retarded in its actuation when it is moved from its left-hand to its right-hand position but is heavily retarded when it is actuated from its right-hand position to its left-hand position as a result of which the inverse impulse starts very quickly after deenergization of the code following track relay TR and is prolonged for an appreciable time thereafter.

It should be observed that the retarding resistance r^2 is effective when either of the two windings of the relay is energized or deenergized whereas the retarding resistance r^3 and rectifier R are only effective during deenergization of the circuit for the upper winding and during energization of the lower winding of the relay. In other words, a relatively long delay in the starting of the movement of the armature of the relay IM takes place upon energization of the lower winding but very little such delay takes place upon energization of the upper winding, it being remembered that these windings when energized are energized to produce magnetism of opposite magnetic polarities in the relay.

In discussing the operating characteristics of this relay IM further it should be understood that the primary purpose of the shunting path including resistance r^2 is to retard the collapse of the flux in the relay structure upon opening of the circuit for the lower winding in order that the retained flux be of sufficient magnitude and retained long enough to assure completion of the stroke of the relay armature and the movement of the contacts from right to left. This shunting path incidentally also causes a very slight retardation in the building up of the flux in the relay when the upper winding is energized through its energizing circuit. This latter effect is undesirable in that it retards the speed of operation of the contacts from left to right upon energization of the upper winding of the relay but this undesirable retardation is entirely overcome by making the energizing circuit for the upper winding a quick acting circuit by having a low reactance-to-resistance ratio. In order to

greatly retard the operation of the relay contacts from right to left the shunting path including resistance r^3 in multiple with the upper winding of this relay includes a rectifier which permits demagnetizing current to flow in the upper winding when the lower winding is energized as well as when the upper winding is de-energized. This flow of demagnetizing current when the lower winding is energized causes retardation of movement of the armature and contacts from right to left and this flow of current due to deenergization of the upper winding causes retention of the flux long enough to assure completion of the stroke of the armature in its movement from left to right. Not only is the series resistance r^4 employed to overcome the armature movement retarding effect above mentioned, but it is also employed to greatly increase the speed of movement of the armature and contacts of the relay from left to right. It is of course understood that the inclusion of the resistance r^4 in the circuit for the upper winding in itself does not increase the speed of build up of current in this winding unless this is accompanied with the application of a proportionally higher voltage. The ohmic value of the resistance r^3 is so chosen as to produce the proper delay in the starting of movement of the armature and contacts from right to left to produce the proper duration of inverse code impulse.

Operation.—Let us assume that the coding relay CR in response to control by coder CT1 picks up to apply a driven code impulse 25 of the 180 impulses per minute rate to the exit end of the track circuit for section 2 of block M. This code impulse 25 (see line 1 of Fig. 2) flows from the positive terminal of the track battery B², front contact 35 of coding relay CR, along the lower rail 10 through the contact 21 of the impulsing relay IM assuming its left-hand position and through the code following track relay TR back through the upper rail 10 to the negative terminal of the track battery B². Driven code impulses 25 have been illustrated in line 1 of Fig. 2 and the current flow in the winding of the relay TR has been shown by dashes in line 2 of Fig. 2. The track relay TR is preferably a polar relay which is so connected to the track rails as to respond to this impulse of current and cause lifting of its contact 14. Although the track relay TR is quick acting the closure of its front contact 14 is somewhat delayed as illustrated by the lag in the dashes in line 3 as compared with the dashes in line 2 of Fig. 2 of the drawing. This delay is in part due to the shunting effect upon the relay winding produced by the track ballast resistance.

Closure of the front contact 14 of the code following track relay TR closes an energizing circuit for the track repeater relay TP. This causes an impulse of current to flow (see dashes in line 5 of Fig. 2) in the track repeater relay TP in time phase with the closure of front contact 14 of relay TR (see dashes in line 3 of Fig. 2). This track repeater relay TP is slightly slow acting and its front contacts 15 and 16 will not close until a short time after energization of its winding as shown by the off-set in the dashes in line 6 of Fig. 2 as compared with the dashes in line 5 of this figure of the drawing.

Upon cessation of the impulse of the driven code (lines 1 and 2 of Fig. 2) the track relay TR will drop its contact 14 and will close an energizing circuit through back contact 14 of this relay TR and through front contact 15 of the

track repeater relay TP resulting in the closure of an energizing circuit for the upper winding of the impulsing relay IM as shown by the dashes in line 8 of Fig. 2. It will be noted that these dashes (line 8 of Fig. 2) start at the point in time when the back contact of the track relay TR closes as illustrated in line 4 of Fig. 2 as emphasized by the dotted line 23, the maximum duration of the impulse applied to the impulsing relay IM terminating when the front contact 15 of the track repeater relay TP opens as illustrated by the end of the dash in line 6 and so emphasized by the dotted line 24. Since, however, the impulsing relay IM is very quick acting and since its energizing circuit may be self-interrupted by the opening of its own polar contact 20 the period of energization of the impulsing relay IM is in practice somewhat shorter as illustrated by the dotted line 27.

As soon as the impulsing relay IM has operated its contacts 20 and 21 to the right-hand position, which occurs substantially simultaneously with the opening of these contacts in movement from their left-hand position as signified by the dotted line 27, the application of an inverse code impulse to the track circuit, as illustrated by the square dotted lobes 26 in line 1 of Fig. 2, begins. Also, as soon as the impulsing relay IM assumes its right-hand position a local energizing circuit through its lower winding and its right-hand contact 20 is established as indicated by the dash in line 10 of Fig. 2. This application of current to the lower winding of relay IM is of the same duration and occurs simultaneously with the impulse of the inverse code applied by the contact 21 to the track circuit of section 2, as illustrated by the dotted inverse code lobe 26 in line 1 and the dash in line 10 of Fig. 2 of the drawing.

It will be observed from the time chart of Fig. 2 that the impulsing relay IM remains in its right-hand position much longer than in its left-hand position. This is by reason of the fact that both of the windings of the relay produce a retarding effect when the lower winding of the relay is energized whereas only the lower winding produces a retarding effect when the upper winding is energized, and also because the retarding effect of the upper winding is much more pronounced. This feature will cause the inverse impulse to be of substantial duration but will cause it to occur very quickly after the driven impulse has ceased. This is important because the time interval between the driven impulse and the inverse impulse is lost time and should be as short as possible.

The last line 11 of Fig. 2 illustrates the duration of time, during the transmission of a 180 impulse per minute code, in which the contacts 20 and 21 of the impulsing relay IM assume the left-hand position. It will be observed that left contact 21 is closed during the entire period of the driven code impulse with ample margin. Also, from the parallelogram illustrated in Fig. 2 of the drawing comprising the dashes 30 and 31 in lines 2 and 5 of Fig. 2 connected by dotted lines 32 and 33 it will be seen that the dashes 30 and 31 are of the same lengths. This signifies that the impulses repeated by the apparatus shown at the entrance end to section 2 of block M from this section into the exit end of section 1 of this block M are of the same duration as the driven impulses flowing in the track circuit of the section 2. In other words, the driven code is re-

peated from the track circuit of the section 2 into the track circuit of the section 1 without material modification of the duration of its impulses. This is necessary where codes are repeated a number of times to prevent the repeated impulses from eventually getting too long or too short to be effective.

The same apparatus of applicant's invention it will be observed is used for repeating a driven code from one track circuit into the next track circuit in the rear and is also used for producing inverse code impulses which are of much shorter duration and which fit into the "off" periods between the impulses of the driven code.

It should be understood that if desired the entrance end of the section 1 of block M may be provided with apparatus similar to that shown at the entrance end of section 2 and that this apparatus may be used to control decoding apparatus for manifesting whether the transmitted code is a 180 impulse, a 120 impulse or a 75 impulse per minute code. This decoding apparatus when used is preferably controlled through the medium of the front contact 17 of the track repeater relay TP for the particular track circuits where devices are to be distinctively controlled in accordance with the code received.

The inverse code impulses, which are produced by the contact 21 of the impulsing relay IM assuming its right-hand position intermittently as illustrated by the dotted lobes 26 in line 4 of Fig. 2, reach the right-hand or exit end of the section 2 at the time when the contact 35 of the coding relay CR assumes its deenergized position. This is true irrespective of whether driven codes of 180, 120 or 75 impulses created by coding contacts CT1, CT2 or CT3, respectively, are transmitted. These inverse code impulses are therefore applied to the slow dropping inverse code track relay ITR and result in continuous energization of this relay ITR in spite of the intermittent nature of the code impulses received. This inverse code following track relay ITR may, as through the medium of its contact 36, control approach lighting circuits for a signal located at the entrance end to the block in advance, may be used for controlling highway crossing signals or may be used for placing an opposing headblock signal in an absolute-permissive-block signaling system to stop.

The applicant has thus provided apparatus whereby driven codes of either the 75, 120 or 180 impulse per minute rate may be decoded to manifest whether the 75, 120 or 180 impulse per minute code has been received; may be used to generate an inverse code the impulses of which fall into the "off" periods of the driven code and which inverse impulses are of considerably shorter duration and which apparatus may also be used for repeating the impulses of the driven code into the next track circuit in the rear in a manner to create impulses of the same duration as are the driven impulses of the code repeated. This apparatus includes a quick acting track relay TR, a rather quick acting track repeater relay TP and an impulsing relay which is controlled through a back contact of the track relay and a front contact of the track repeater relay and which impulsing relay is very quick acting in operating to its inverse-code position but is rather slow acting in returning to its driven-code-receiving position and in which the impulsing relay is self-actuating insofar as its return to its driven-code-receiving position is concerned.

It may be pointed out here that the impulsing

relay IM is of a construction to cause so-called door-bell actuation if its main energizing circuit through contacts 14 and 15 of relays TR and TP is continuously closed at these contacts 14 and 15, and that upon such continuous closure of these contacts 14 and 15 the impulsing relay IM would intermittently operate from one position to the other and in each operation would dwell in its right-hand position much longer than it would in

- 10 its left-hand position. It is readily seen from Fig. 2 of the drawing that such intermittent so-called door-bell actuation of the impulsing relay IM will not take place in practice because the front contact 15 of the track repeater relay TP 15 opens before the impulsing relay IM has had an opportunity to return to its left-hand position, this is indicated by the fact that the dashes in line 6 of Fig. 2 of the drawing terminate after the dashes in line 9 of Fig. 2 of the drawing begin. 20 That is, such door-bell actuation can take place in point of time only between dotted lines 23 and 24 and this allows time only for one actuation toward the right.

Having thus shown and described one rather specific embodiment of the invention it is desired to be understood that the particular embodiment shown has been selected for the purpose of facilitating describing the underlying principles of the invention and the functions which the apparatus of the invention is to perform and that the particular embodiment illustrated has not been selected to show all possible forms that the structure of the present invention may take and that various changes, modifications and additions 35 may be made, as required to meet the particular problem in practicing the invention, without departing from the spirit or scope of the invention except as demanded by the scope of the following claims.

40 What I claim as new is:

1. In a railway block divided into two sections by insulating joints the first section of which is first occupied by a train moving in the normal traffic direction, a track circuit for each section including a source of track current at the exit end and a code following track relay at the entrance end, driven code creating means at the exit end of the second section for transmitting a driven code from the exit end toward the entrance end of said second section, a relatively quick acting track repeater relay and an impulsing relay at the entrance end of said second section, said impulsing relay being a two-position relay constructed to remain in its last operated position until again operated and having two windings and contacts for closing at one point an energizing circuit including one winding and a current source when such relay assumes the normal position and closing the other winding in an energizing circuit including a current source when such relay assumes the reverse position, light retarding means associated with said impulsing relay and effective when said one winding is energized, heavy retarding means associated 60 with said impulsing relay effective when said other winding is energized, said energizing circuit for said one winding also including a front contact of said track repeater relay and a back contact of said code following track relay, a front contact on said track repeater relay for repeating said driven code from said second section into said first section, and contacts on said impulsing relay for connecting said code following track relay of said second section and an inverse code source into the track circuit of said second sec-

tion when said impulsive relay assumes its normal and reverse position respectively.

2. In a railway track block divided into two sections the first section of which is first occupied by a train moving in the normal traffic direction, a track circuit for each section including a source of track current at the exit end and a code following track relay at the entrance end, driven code creating means at the exit end of the second section for transmitting a driven code from the exit end toward the entrance end of said second section, a relatively quick acting track repeater relay and an impulsive relay at the entrance end of said second section, said impulsive relay being a two-position relay constructed to remain in its last operated position until again operated and having two windings and contacts for closing at one point an energizing circuit including one winding and a source of current when such relay assumes the normal position and closing the other winding in an energizing circuit including a current source when such relay assumes the reverse position, light retarding means associated with said impulsive relay and effective when said one winding is energized, heavy retarding means including said light retarding means associated with said impulsive relay and effective when said other winding is energized, said energizing circuit for said one winding also including a front contact of said track repeater relay and a back contact of said code following track relay, a front contact on said track repeater relay for repeating said driven code from said second section into said first section, and contacts on said impulsive relay for connecting said code following track relay of said second section and an inverse code source into the track circuit of said second section when said impulsive relay assumes its normal and reverse position respectively, said heavy retarding means and said light retarding means having retarding relationships such that the inverse code impulse very closely follows the termination of the driven code impulse and terminates considerably before the next driven code impulse begins.

3. In a railway track block divided into two sections by insulating joints the first section of which is first occupied by a train moving in the normal traffic direction, a track circuit for each section including a source of track current at the exit end and a code following track relay at the entrance end, driven code creating means at the exit end of the second section for intermittently connecting the source of track current to the rails of said second section to create a multiple impulse driven code in the track circuit of said second section, a track repeater relay and a polar impulsive relay of the two-position type at the entrance end of said second section and constructed to remain in its last operated position until again operated, an inverse code current source, a first winding for said impulsive relay included in a circuit including a front contact of said track repeater relay a back contact of said track relay and contacts of said impulsive relay closed when such impulsive relay assumes a first position and including a source of current of a polarity to operate the relay to a second position, a second winding for said impulsive relay included in a circuit including contacts of such impulsive relay closed when such impulsive relay assumes said second position and including a source of current of a polarity to operate the relay to the said first position, other contacts on said impulsive relay for connecting the associated code

following track relay or said inverse code current source to the track rails of said second section in response to said impulsive relay assuming said first or said second position respectively, means associated with said impulsive relay for slightly retarding operation of such relay when it is energized through the medium of said first winding and for heavily retarding operation of such relay when it is energized through the medium of said second winding, and a front contact of said track repeater relay included in series with the source of track current of the track circuit of said first section.

4. In a railway track block divided into two sections by insulating joints the first section of which is first occupied by a train moving in the normal traffic direction, a track circuit for the second section of said block including a source of track current at the exit end and a code following track relay at the entrance end, driven code creating means at the exit end of the second section for intermittently connecting the source of track current to the rails of said second section to create a multiple impulse driven code in the track circuit of said second section, a track repeater relay and a polar impulsive relay of the two-position type at the entrance end of said second section, an inverse code current source, a first winding for said impulsive relay included in a circuit including a front contact of said track repeater relay a back contact of said track relay and contacts of said impulsive relay closed when such relay assumes a first position and also including a source of current of a polarity to operate the relay to a second position, a second winding for said impulsive relay included in a circuit including contacts of said impulsive relay closed when such relay assumes said second position and including a source of current of a polarity to operate the impulsive relay to the said first position other contacts on said impulsive relay for connecting the associated code following track relay or said inverse code current source to the track rails of said second section depending upon whether said impulsive relay assumes said first or said second position respectively, and means associated with said impulsive relay for slightly retarding operation of such relay when it is energized through the medium of said first winding and for heavily retarding operation of such relay when it is energized through the medium of said second winding.

5. In combination, a pair of track rails upon which the impulses of a driven code are impressed, a code following track relay, an inverse code battery, a track repeater relay controlled through a front contact of said code following track relay, an impulsive relay operated to one position through the medium of a first circuit including a source of current a front contact of said track repeater relay and a back contact of said code following track relay, and operated to the other position through the medium of a second circuit for said impulsive relay including a source of current and its own contact closed only when said impulsive relay assumes said one position, contacts on said impulsive relay for connecting said code following track relay to said track rails when said impulsive relay assumes said other position and for connecting said inverse code battery to said track rails when said impulsive relay assumes said one position, and means for retarding the operation of said impulsive relay to a slight extent when said first circuit

is energized and retarding it to a greater extent when said second circuit is energized.

6. In combination, a pair of track rails upon which the impulses of a driven code are impressed, a code following track relay, an inverse code battery, a track repeater relay controlled through a front contact of said code following track relay, an impulsive relay operated to one position through the medium of a first circuit including a source of current, a front contact of said track repeater relay and a back contact of said code following track relay, and operated to the other position through the medium of a second circuit including a source of current its own contact and closed only when said impulsive relay assumes said one position, contacts on said impulsive relay for connecting said code following track relay to said track rails when said impulsive relay assumes said other position and for connecting said inverse code battery to said track rails when said impulsive relay assumes said one position, means for retarding the operation of said impulsive relay to a slight extent when said first circuit is energized and retarding it to a greater extent when said second circuit is energized, a track section adjacent said pair of track rails having a track circuit including a source of track current, and a front contact of said track repeater relay included in series with said source of track current in said adjacent track circuit for repeating said driven code into said adjacent track circuit.

7. In combination, a pair of track rails, a code following track relay periodically energized under favorable traffic conditions, an inverse code battery, a track repeater relay controlled through a front contact of said code following track relay, an impulsive relay operated to one position through the medium of a first circuit including a front contact of said track repeater relay and a back contact of said code following track relay and a source of current, and operated to the other position through the medium of a second circuit including a source of current and its own contact closed only when said impulsive relay assumes said one position, contacts on said impulsive relay for connecting said code following track relay to said track rails when said impulsive relay assumes said other position and for connecting said inverse code battery to said track rails when said impulsive relay assumes said one position, and means for retarding the operation of said impulsive relay to a slight extent when said first circuit is energized and retarding it to a greater extent when said second circuit is energized, a track section adjacent said pair of track rails but insulated therefrom and provided with a track circuit having a source of track current at the adjacent end, and a front contact of said track repeater relay included in series with said source of track current.

8. In combination, a pair of track rails, a code following track relay periodically energized under favorable traffic conditions, an inverse code battery, a track repeater relay controlled through a front contact of said code following track relay, an impulsive relay operated to one position through the medium of a first circuit including a source of current a front contact of said track repeater relay and a back contact of said code following track relay, and operated to the other position through the medium of a second circuit including a source of current its own contact and closed only when said impulsive relay assumes said one position, contacts on said impulsive relay for

connecting said code following track relay to said track rails when said impulsive relay assumes said other position and for connecting said inverse code battery to said track rails when said impulsive relay assumes said one position, and a rectifier and a resistance unit included in series therewith and included in multiple with a winding of said impulsive relay with the rectifier so poled that very little current flows therethrough when said first circuit is energized but a large amount of current flows therethrough when said second circuit is energized to retard the operation of said impulsive relay to a slight extent and a great extent respectively as said first and said second circuit are energized.

9. In a driven coded and an inverse coded track circuit, a pair of track rails, a code following track relay at times connected across the track rails at one end, means for applying a driven code consisting of periodic impulses of current across the track rails at the other end, a repeater track relay controlled through a front contact of said code following track relay, an electro-responsive device having two windings and constructed to be operated quickly to one position when one winding is momentarily energized and operated less quickly to the opposite position when the other winding is momentarily energized, a circuit for momentarily energizing said one winding including a source of current a front contact of said repeater track relay and a back contact of said code following track relay, a circuit for momentarily energizing said other winding including a source of current, a contact closed when said electro-responsive device assumes said one position, an inverse current source, and contact mechanism operated by said electro-responsive device for connecting said code following track relay across the track rails when said electro-responsive device assumes said other position and connecting said inverse current source across the track rails when said electro-responsive device assumes said one position.

10. In a driven coded and an inverse coded track circuit, a pair of track rails, a code following track relay at times connected across the track rails at one end, means for applying a driven code consisting of periodic impulses of current across the track rails at the other end, a repeater track relay controlled through a front contact of said code following track relay, an electro-responsive device having two windings and constructed to be operated quickly to one position when one winding is momentarily energized and operated less quickly to the opposite position when the other winding is momentarily energized, a circuit for momentarily energizing said one winding including a source of current a front contact of said repeater track relay and a back contact of said code following track relay, a circuit for momentarily energizing said other winding including a source of current a contact closed when said electro-responsive device assumes said one position, an inverse current source, contact mechanism operated by said electro-responsive device for connecting said code following track relay across the track rails when said electro-responsive device assumes said other position and connecting said inverse current source across the track rails when said electro-responsive device assumes said one position, and code responsive means controlled by said repeater track relay.
